AWNING FASTENING DEVICE

Charles W. Gasswint, Mason City, Iowa

Application August 17, 1934, Serial No. 740,331

3 Claims. (Cl. 156—44)

The present invention relates to awnings and like structures, and has for an object to provide means for bracing the awning against rising and flapping and holding the same rigid even in the 5 strongest wind.

The invention provides an improved brace which may be attached to various types of awning frames after the same have been installed, which may be disengaged when the awning is 10 to be folded and wound and secured in an out of the way position, and which securely holds the awning frame lowered or extended when adjusted thereto.

The invention also provides a brace having a 15 movable part and a coupling on the awning frame quickly detachable from the movable part, so that a slight turn or movement of the hand is sufficient for securing the brace in place and also in releasing the brace, all movable and securing parts being readily movable and quick acting.

Another feature of the invention is to provide a brace which may be applied to awnings of 20 different sizes and which will not interfere with foot or other traffic passing beneath the awning.

With the foregoing and other objects in view, the invention will be more fully described hereinafter, and will be more particularly pointed out in the claims appended hereto.

30. In the drawing, wherein like symbols refer to like or corresponding parts throughout the several views,

Figure 1 is a side elevation of a conventional type of awning having the improved fastening device applied thereto, the dotted lines showing the fastening device swung back out of the way.

Figure 2 is an enlarged fragmentary side elevation of the detachable coupling used for holding the fastening device in position.

40. Figure 3 is a transverse section taken through the same substantially on the line 3—3 of Figure 2.

Figure 4 is a fragmentary section similar to Figure 3, but showing the clamping nut released, 45 and

Figure 5 is an end view of the coupling bolt used.

Referring now to the drawing, the improved fastening device or brace is shown as applied 50 to one form of awning, although different types or forms of awnings may be used. The awning comprises a fabric sheet 10 secured at its upper end to a roller 11 upon which the sheet 10 is wound when the awning is raised. The roller 11 is supported in suitable brackets 12, which may

be secured against the outer face of a wall 13, or the like, upon which the awning is hung.

The outer or lower end of the sheet 10 is connected to a swinging arm 14, which, as shown in Figure 1, when in open position extends substantially horizontally outward from the wall 13. The inner end of the arm 14 is connected by a pivot 15 to a bracket 16 secured against the wall 13. The arm 14 is adapted to be swung upwardly against the wall 13 and beneath the roller 11 when the awning is raised.

In high wind, particularly, the awning sheet 10 and the arm 14 are raised, and as the wind pressure varies the awning vibrates or flaps and this movement is not only objectionable as to the noise 15 and vibration, but is also destructive to the awning itself. To overcome this the present invention provides a brace arm 17 which is connected by a pivot 18 to a brace bracket 19 secured against the wall 13 at a point above the awning arm 20 bracket 16. The outer or free end of the brace arm 17 is provided with a flat coupling portion or ear 20 provided with a longitudinal slot 21, the intermediate portion of which is enlarged and rounded to provide a circular opening 22 which opens at opposite sides into the opposite ends of the slot 21.

A clamp 23 is adjustably mounted upon an intermediate portion of the awning frame arm 14, and in the present instance is shown as comprising a pair of opposed jaw members recessed at their inner sides to embrace the arm 14, and which at their lower ends have abutting flanges 24 through which is secured a clamping screw 25 having the usual nut for binding the lower ends of the clamp elements on the arm 14. The upper ends of the clamp elements are of increased thickness and are provided with recesses 26 in their outer sides which are disposed in relative alignment and which open into axially aligned openings for the reception of one end of the shank 27 of a combined clamping and coupling bolt. The end 27 of the bolt is threaded at its extremity to receive a threaded nut or washer 28, which is seated in one of the recesses 26. The intermediate portion of the clamping bolt is provided with an enlarged circular head 29 which partially seats in the recess 26 at the opposite side of the clamp 23 and which is of slightly less diameter than that of the opening 22 of the ear 20. The ear 20 thus partially fits over the head 29, and the opposite end of the shank 27 is screw threaded and receives thereon a winged nut 30 which has a hub portion corresponding substantially in diameter to that of the head 29, so that the hub portion 55

of the nut may freely pass through the circular opening 22 in the ear 20.

For the purpose of holding the nut 30 to the shank of the bolt and preventing loss of the nut, 5 the bolt is provided with a kerf 31 in its outer end by means of which the bolt may be turned or held stationary during the fastening of the nut 28 in position. The kerf 31 also provides a split in the end of the bolt, so that the opposite portions 10 of the bolt may be spread, as shown at 32 in Figure 4, to form an up-set on the end of the bolt holding the nut from being backed off entirely therefrom.

The wings 33 of the nut 30 are diametrically 15 opposed on the hub of the nut and are proportioned relatively to the ends of the slot 21 such that, when the nut is turned to register the wings 33 with the slot 21, the ear 20 may be readily drawn outwardly over the nut and away from the 20 clamp 23. The pivot 18 of the brace arm 17 is sufficiently loose to admit of this lateral swinging of the brace 17 to the necessary extent for releasing 25 and coupling the outer end of the brace with reference to the awning frame arm 14. It will be noted that the wings 33 are provided with straight 30 inner edges adapted to bind against the outer face of the ear 20 when the winged nut 30 is turned into an angle with reference to the slot 21, as shown in Figure 2. The pitch of the threads of the bolt 27 is such that the initial movement of 35 the nut out of line with the slot will clear the wings 33 from the edge of the slot, and will gradually advance the nut toward the clamp 23 so as to bind the wings 33 against the ear 20 and in turn force the latter over against the clamp. The brace arm 17 is thus rigidly clamped in position 40 so that any pressure of wind beneath the awning or against the underside of the arm 14 is resisted by the diagonally disposed brace and thus the awning is maintained rigidly in open position.

When it is desired to raise the awning, it is 45 only necessary to back off the winged nut 30 to release the clamping pressure of the nut from the ear 20, and to bring the wings 33 into register with the slot 21. The brace 17 with its ear 20 is now swung laterally from the clamp 23 to disengage the brace therefrom. The brace 17 may be then positioned against the wall 13 and suspended from its pivot 18. If desired a clamp 50 bracket 34 may be secured against the wall 13 below the awning frame bracket 16 to register with the ear 20 when swung backwardly out of the way. The bracket 34 is provided with a similar nut to that shown at 30, so that the ear 20 may be rigidly clamped to the bracket 34 for holding the brace 17 firmly in an out of the way position.

This improved awning fastening device may be applied to awning frames or arms of various constructions wherein it is desirable to hold the arms 55 from swinging or buckling upward.

It is obvious that various changes and modifications may be made in the details of construction and design of the above specifically described embodiment of this invention without departing from the spirit thereof, such changes and modifications being restricted only by the scope of the following claims.

What is claimed is:—

1. A fastening device for awnings having a pivotally mounted frame arm, comprising a brace arm, a pivotal bracket connected to one end of the brace arm and adapted to be mounted above the pivotal support of the awning frame arm, said brace arm having at its free end a longitudinally slotted ear with an opening therethrough intersecting the slot, a clamp adjustably mounted on the awning frame arm, a coupling bolt carried by the clamp, and a winged nut mounted on the bolt for passage through the opening in the ear when the wings of the nut register with the slot, said nut adapted to be turned for binding the wings against the outer side of the ear to clamp the latter against said clamp.

2. A fastening device for awnings having a downwardly swinging frame arm, a diagonal brace 25 having a pivotal support above said frame arm and having a slotted and apertured ear at its free end, a clamp adjustably mounted on the awning arm, a threaded bolt carried by the clamp and extending outwardly therefrom for receiving 30 the ear thereover, and a winged nut carried by the bolt for passage through the aperture and slot of the ear, said nut being adapted to be turned up against the ear for binding the same to the clamp.

3. A fastening device for awnings having an outwardly swinging arm, comprising a brace arm, a bracket pivotally mounted on one end of the brace arm and adapted to be mounted in vertically spaced relation to the awning arm, a clamp comprising a pair of opposed elements adapted to embrace the awning arm, a clamping bolt engaging through the adjacent ends of the elements at one side of the arm, a combined clamping and coupling bolt having a shank portion engaging through the other ends of the elements for binding the same to the awning arm, said elements having recesses in their outer side about said combined bolt, a nut on one end of the bolt seated in one of said recesses, a head on the intermediate portion of the bolt partially seated in the opposite recess, said brace arm having a flat apertured and slotted ear at its free end, said ear adapted to engage the clamp with said head of the bolt partially engaging in the opening of the ear, and a winged nut threaded upon the outer end of the combined bolt for passage through the opening and the slot in the ear and adapted to be turned up against the ear to secure the same to the clamp.
